UNITED STATES PATENT OFFICE.

FREDERICK E. MAYNARD, OF BERKELEY, CALIFORNIA.

RAT-GUARD.

1,160,634.

Specification of Letters Patent.

Patented Nov. 16, 1915.

Application filed November 24, 1913. Serial No. 802,651.

To all whom it may concern:

Be it known that I, FREDERICK E. MAYNARD, citizen of the United States, residing at Berkeley, in the county of Alameda and State of California, have invented new and useful Improvements in Rat-Guards, of which the following is a specification.

This invention relates to rat guards.

The present invention has for its object 10 to provide a rat guard which is of few parts inexpensively made and readily assembled; to provide a guard designed to withstand the abuse encountered in use and storage, and which can be readily repaired when 15 damaged.

A further object is to provide a guard with practically one main sheet substantially encompassing a support to be guarded and having a small shutter to complete the 20 encompassment.

A further very important object of the invention is to provide a rat guard which will of its inherent structure be rat-proof when adjusted upon a support and to provide 25 such a device as can be applied readily, quickly and effectively without depending upon the particular attention of a careless, unskilled or disinterested hand or seaman.

It is very important that a rat guard be 30 adjustable to snugly fit any hawser or other support upon which it may be mounted so that rodents may not pass the barrier by finding small apertures at or about the support through which they can pass without 35 attempting to jump over the guard. In my Patent No. 1,060,993, granted May 6th, 1913, I claimed and made provision for the snug clamping of the support by means of flexible, split clamps which could be drawn 40 down close together upon the rope and then fastened by suitable means. This proved very effective and I have utilized this clamp means in my present invention.

Another valuable feature of this invention 45 is the provision of a guard of such structure that a number of them may be closely nested and stored for the conservation of space, particularly in ships where every cubic foot of space is valuable.

Primarily the object of this invention is 50 to provide a rat guard of one piece as nearly as is practicable with means for making a snug fit upon supports of various diameters.

The invention consists of a barrier mem- 55 ber nearly encompassing a support with a supplemental shutter completing the en-

compassment and with clamps adapted to be snugly closed upon the support to prevent the passage of rats therealong.

Figure 1 is perspective view of the improved guard as applied to a ship's hawser. Fig. 2 is a front view of the guard open for application to the hawser. Fig. 3 is a side elevation of the guard. Fig. 4 shows a slight variant of the pivot location. Fig. 5 shows 65 guards nested.

This invention pertains particularly to a device comprising a barrier structure adjustable upon ship's hawsers and various other supports along which rats or other 70 animals are likely to pass. The barrier must be of sufficient diameter to prevent the animal climbing or jumping over the same and the guards I construct are 36" in diameter in compliance with Federal regulations. Not 75 only must they be of sufficient size but must also snugly fit the support in whatsoever manner they may be mounted thereon. This important feature is provided for in guards involving clamps shown in my patent above 80 mentioned and which are successfully in use and have passed Federal inspection and been approved.

The present improvement relates to the barrier structure which consists of a sub- 85 substantially one-piece disk —2— entirely encompassing the hawser —3—, or other support, save for a radial slot —4— which may be of a width to receive a given size line —3— to which the disk stands perpendic- 90 lar.

Extending at right angles to the side of the disk is a carrier —5— securely fastened to the disk in any suitable manner as by angle braces —6—. The carrier —5— may 95 be of substantially equal diameter to the width of slot —4— and is coincident with the inner end of the same.

In order to close the slot —4— after the guard is in place on the support there is provided a shutter plate —7— hooked over the edge of the disk at —8— and pivoted in such manner that it may be swung open to clear the slot for the reception of the line —3—. The inner end of the shutter is de- 100 signed to form, when closed, a hole through the guard disk —2— to receive the line. Thus the disk is secured perpendicularly to the carrier member —5— and when set upon the line and the shutter closed thereover the 105 line is completely encompassed.

The shutter is shown as having extending

from one side a semi-tubular piece —9— forming with the carrier —5— a sleeve to encompass the given line and in Figs. 1, 2 and 3 there is shown the sleeve members —5— and —9— hinged at —10— to form the pivotal relation between the disk and the small shutter, though the pivot may be located at —10'—, Fig. 4.

To make a guard effectively rat-proof upon lines less than given size for which the disk is slotted the ends of the sleeve members are slit at —12— to form prongs —13— which may be drawn together to snugly clamp and encompass the line or other support —3— by any suitable means, as a piece of light rope —14—. One end of the rope may be fast in an eye —15— of a brace —6—.

By so arranging braces —6— that their arms lie along the edges of the carrier —5— the latter will be greatly reinforced and if the shutter is hinged as at —10— the hinge is strengthened by the contiguous brace.

Only one brace —6— is necessary to reinforce the shutter and its clamp piece —9— which may have a flange device riveted to the inner end of the shutter.

The sleeve structure may be made tapering, if desired, so that the guards can be very closely nested for storage when removed from the support —3— as in Fig. 5.

When the guard is to be applied to a ship's line it is only necessary to open the shutter and drop the disk down so that the line enters the radial slot, after which the shutter is swung over the slot and the rope binder wrapped around the clamp. During this operation the guard is entirely supported by the line and herein lies a great advantage by the reduction of the liability to lose the guard overboard when the guard is made in large, divided, unwieldy sections which must be opened and closed about a pivot to receive a line.

There is no possibility that shutter can be pulled laterally from the disk and thus bend the latter or strain the pivot because the shutter is hooked over the edge of the disk and can only move angularly.

To form the slot —4— the sheet may be slitted to the center on a radial line and the side edges folded back as at —16— the folded stock being utilized to reinforce the disk along the edges of the slot and at the same time avoiding waste.

In lieu of the braces —6— the carrier

—5— may be secured to the disk in any suitable manner and the desired stiffness of the disk obtained by radial embossing as at —17—, Fig. 4.

Having thus described my invention, what I claim, and desire to secure by Letters Patent, is

1. A rat guard comprising a disk adapted to substantially encompass a support and having a radial slot extending from its center to its circumference, a supplemental shutter slidably related to the disk to cover and uncover the slot, and complementary clamp members on the disk and shutter closable about the support. 70

2. A rat guard comprising a disk adapted to substantially encompass a support and having a radial slot of width approximating a given size support and extending from the center of the disk to its circumference, 75 a supplemental shutter adjustably connected to said disk and movable over the slot, and complementary parts attached to said member and the shutter and adapted to be snugly clamped about the support to prevent the 80 passage of animals therewith.

3. A rat guard comprising a disk with a radial slot to receive a support, complementary means for securing the disk in a perpendicular position on and for inclosing 85 the support, and a shutter for covering and uncovering the slot and having a close planary relation therewith, said means including sleeves on the disk and the shutter.

4. A rat guard comprising a disk with a 90 radial slot to readily receive a support, and a shutter pivotally related to the disk and movable over the slot and having a part overlapping the edge of the disk to prevent any but a pivotal movement of the shutter. 95

5. A rat guard comprising a disk with a radial slot to readily receive a support, and a shutter slidably related to the disk and movable over the slot, the shutter overlapping the edges of the slot and being held 100 against lateral movement from the plane of the disk, said members having clamp sleeves for embracing the support.

In testimony whereof I have hereunto set my hand in the presence of two subscribing 105 witnesses.

FREDERICK E. MAYNARD.
